HEAT REGULATOR

Perry S. Martin, Harrisonburg, Va.

Application December 6, 1941, Serial No. 422,012

8 Claims. (Cl. 236—95)

1

This invention relates to draft regulating devices and has for its principal object the provision of a simple and efficient regulator for use with space heaters burning solid fuel.

A further object of the present invention is to provide a regulator for wood and coal burning stoves of a type which will keep the fire in the stove for a long period of time and meanwhile will hold the heat of the room at a constant degree within a small margin.

A still further object of the present invention is the provision of a regulator for a coal or a wood burning stove which will respond almost entirely to the temperature of the room when the room is at the normal temperature desired and which will to some extent respond to the heat of the stove should the room temperature be below normal, thus giving an anticipating action to the control.

Other objects of the invention relate primarily to details and are more specifically set forth in the claims.

With the present day electric thermostatic controls there is no difficulty of any kind in maintaining a room at a closely regulated degree and this is still more true where the fuel is liquid or gaseous. There are, however, many dwellings in which electrically controlled devices cannot be used, and still many others in which the cost would be prohibitive even were the electricity available. The present regulator is adapted for use with either a coal burning or a wood burning stove.

In the drawings:

Figure 1 is a central section through one form of my device.

Figure 2 is a rear view with the rear panel of the mirror baffle removed.

Figure 3 is a perspective illustrating a portion of the regulator with the casing removed.

Figure 4 is a detail illustrating the knife edge bearing of the regulating lever.

Figure 5 shows the device applied to a coal burning circulating heater.

Referring particularly to Figure 1, the stove illustrated is of the wood burning type and is designated generally by the numeral 10. It has a sheet steel wall 11, a flanged baffle 12 and an opening 14 of the intake of air. Secured around this opening 14 by bolts extending through the baffle is a casting 16 which is usually especially made for the particular style of stove and may be sold with either the stove or the regulator or both. The major parts of the regulator are the

2

draft tube 18, the frame work or chassis 19 supporting the thermostat 20 and the casing 21.

The draft tube 18 is square in vertical cross section, snugly fitting the casting 16 and being bolted thereto as at 23, by means of a pair of brackets 24 spot welded to the end of the draft tube. The rear of the draft tube slopes at an angle of about 45° providing a large opening 25 which is closed by the main damper 26 pivoted on rod 27 extending thru the side walls to the draft tube and being held against side to side movement by the two walls of the casing 21. A pilot valve 30 is loosely pivoted to the main damper 26, as at 31, and carries a zigzag member 33 serving a dual function, to limit the opening of the pilot valve 30 and to afford attachment for the controlling chain 34 which not only pulls the pilot valve closed, but preceding this act, pulls the main damper shut. The upper surface of the pilot damper is much larger than the opening 36 through the main damper so the resistance to closing of the pilot damper is greater than the resistance to turning of the main damper 26 on its axis 27. This pilot damper therefore opens first and closes last, in this way avoiding a too abrupt opening or closing of the draft.

The principal element of the chassis is a channel member, the web of which is bent at right angles at 37 to form a vertical portion 38 and a horizontal portion 39. The flanges 40 of this member are necessarily severed near the bend 37. The baffle 38 forms one wall of a vertical passageway and the portion 39 forms the floor of a communicating horizontal passageway. Triangular stiffening elements 41 not only strengthen the two arms of the channel member, but likewise afford means for supporting the upper plate 44 which is part of the casing although secured to the chassis.

Mounted on the underside of the web 39 of the channel member is a relatively heavy steel plate 45 which extends rearwardly then downwardly and then slopes at an angle of about 45° from the point 46. As best seen in Figure 4, this 14-gauge plate has a T-slot at its free end, the stem of the slot bearing the numeral 47 and the longer reach of the slot being numbered 48. The regulating lever 50 has a T-head which rests on the sloping portion of the plate 45, thus forming a pair of knife edges 51 which materially adds to the efficiency and ease of control of the regulator. To the bottom of the lever is secured a strap 54, carrying at its lower end the chain 34.

Referring particularly to Figure 3, two small

zigzag bearing members 55 are secured to the flange 40 of the horizontal web of the channel member and in these bearing pieces is mounted a pivot rod 56, endwise movement of which is prevented by engagement with the flanges 40. A quite heavy cam lever 60 is secured to the pivot rod 56 and bears at the end 61 of its horizontal arm on a cam 62 secured to a vertical post 63 passing through the web 39, the plate 45 and the top casing member 44. This post 63, preferably permanently attached to the cam, carries a manual knob 64 turning about a dial 65 which may be marked in arbitrary numerals and with arrows showing warmer in one direction and cooler in the other.

At its lower free end the cam lever 60 is tapped as at 66 to receive the threaded end of the thermostat unit 20, preferably consisting of a plurality of corrugated wafers and having a stud 67 to engage a rounded elevation 68 on the regulating lever.

The major portion of the casing 21 is a single sheet bent like a square U, thus forming the back and the two sides of the regulator. The casing has a plurality of horizontal slots or openings 70 somewhat above the center and has opposed vertical openings 71 above the draft damper when closed and also has a number of similar slots or openings 72 in the rear wall which is otherwise closed. The openings 72 provide for entry of air to the draft tube. The openings 70 allow ventilation of an insulating space, later to be described. The openings 71 allow entry of additional air and primarily afford a view of the draft damper. The slots 74 in the top of the casing are optional but are found to be quite convenient in affording a more sure flow of air under certain conditions.

A channel shaped heat baffle 77 is secured to the flanges 40 of the vertical web 38 of the channel member and also to the triangular stiffening pieces 41. The front wall 78 of this member is chromium plated so as to be heat reflecting, while the inside of this sheet is of the normal dull finish of the steel sheet. A similar piece of chromium plated steel is attached centrally within the frame of the regulator, this consisting of an angular piece 80 spot welded or otherwise secured to the plate 45. Its reflecting surfaces 81 and 82 provide a central ventilated insulating space 85, the front wall of which is the web 38; the rear wall, the portion 82; and the bottom wall, the integral portion 81 of the sheet 80. The two side walls of this space are formed by the two parallel walls of the outer casing, but these are largely removed in this area by the cutting of the slots 70 at both sides. The purpose of this space 85 is to prevent heat from passing from the stove to the thermostat 20. The reflecting surface 78 likewise aids in this feature, as does the web 38. These several members are heated by the radiant heat from the stove and were it not for this ventilated insulating space 85 which cools the surrounding metal, a much greater quantity of heat would be conducted through the metal to the thermostat. I may heat insulate the thermostat from the cam lever 60 by a small fibre washer 84, but in practice do not find this necessary.

The operation of the device is as follows:

The knob 64 is moved to select the chosen heat to be maintained, which action it will be noted raises or lowers the upper end 61 of the lever 60 with consequent increased movement of the anchored end of the thermostat. Assuming the room to be colder than desired, the main damper 26 is wide open, that is horizontal, the stop being

formed by engagement of the damper with the lower end of the strap 54. Under such circumstances air enters through the large space 83 between the edge of the draft tube and the casing and also through the holes 72 in the casing. This air thus flows from right to left in Figure 1, under the open damper entering the stove through the casting 16 and the opening 14.

At the same time there is a slow movement of air from between the reflecting baffle face 78 and the wall 11 of the stove and also inside of the baffle 77. The latter air passes in part through the open end 87 of the reflecting baffle, partly through the optional opening 74 in top of the casing and partly from left to right, in Figure 1, between the web 39 and the upper sheet 44 of the casing, thence downwardly inside of the rear wall 21 of the casing thus passing across the large area of the wafers of the thermostat, heating the latter by this relatively warmer air, which after warming the thermostat passes into the stove across the upper surface of the draft damper 26, being directed in this path by the great quantity of air passing to the stove from the bottom opening 83, this air mostly passing below the draft damper which is now horizontal.

The passage of the small quantity of warmed air is a very important feature as it makes the thermostat far more sensitive to increase in the stove temperature and would check the fire if the heat increased too fast, even though the room were still cold. Radiant heat from the heated wall 11 of the stove passes through the optional openings 88 in the web 38 and this helps to heat the thermostat. The element 90 is a light aluminum baffle adapted to prevent the passage of this radiant heat when the damper is entirely closed.

As the temperature of the stove increases the thermostat expands. Since the screw-carrying anchored end is fixed in space by the positioning of the lever 60, such expansion of the thermostat causes an increased pressure on the ridge 68 of the regulating lever 50 which turns on its knife edge bearings 51 and pulls on the chain 34. The angle of pull plus the weight of the pilot 30 causes a movement of the entire mass pivoted at 27 including the counter-weight 93 and this movement continues as long as the thermostat is expanding; that is, until such time as the main draft damper 26 is entirely closed. The pilot damper is now fully open and an appreciable amount of further expansion of the thermostat is required before the increased pull on the chain 34 closes this pilot damper 30. This is an important feature as it bars all possible sudden cessation of the draft and causes the fire to ease down, which is particularly important with fuel having a high volatile content.

When the heat requirements have thus been met, there is no movement of air from left to right in the upper air passageway of the regulator, that is, between the web 39 and the top wall 44, such heat as may rise passing freely through the openings 74 and 87. There is, however, a movement of room temperature air from the bottom opening 83 upwardly past the thermostat and from right to left in the upper horizontal space above the channel member. Since the metal of the regulator is slightly warmer than the room temperature, this current of air passes out through the openings 74 and 87. As the dampers 26 and 30 are now entirely closed, they also are at a temperature above that of the room. Air follows the heated sloping surface of this

metal and passes out through the opening 81 through the two or more holes 88 in the channel member. The thermostat 20 is quite near the opening 83 so it is bathed almost exclusively in air at the temperature of the room and radiation of heat from the stove is blocked by the reflecting surface 78, the vertical wall of the flanged channel member 19, the ventilated insulating space 85 and the reflecting surface 82. As a consequence, the thermostat at such times is substantially exclusively under control by the room air and responds very quickly to any change in temperature. It will be noted that the bosses 90 provide an air space between the casing and the draft tube and chassis, also that the sheet 80 makes a fairly snug fit with the casing, being wider than the channel member 19.

When used with a coal burning stove as in Figure 5, the regulator is secured to the ash pit 86 by an appropriate casting 89. The slot 91 in the mirror baffle 77 is provided to receive the casing 92 of the circulating heater so as to position this baffle in the space between the stove and its light metal casing. The operation of the regulator when used with a circulating heater is substantially the same as has previously been described.

What I claim is:

1. In a draft regulator for solid fuel burning space heaters, a horizontal draft tube, a draft damper controlling the flow of air therethrough to the heater, a vertical baffle above the draft tube, a reflector cooperating with the vertical baffle to form a vertical passageway adjacent the heater, walls forming a second vertical air passage spaced from the previously mentioned passageway, walls forming a horizontal air passage communicating with the upper ends of the two vertical passageways, a thermostat within the second passageway, and a sloping wall directing heated air from the spaced passage to a point just above the draft tube, whereby when the damper is open heated air will pass upwardly between the baffle and the reflector and thence downwardly past the thermostat, thus making the thermostat more responsive to changes in the heater temperature when the damper is open and the room is cool than it would be if the heated air were not thus circulated.

2. In a regulator for a solid fuel burning space heater, walls forming a heat insulating space ventilated to the room to be heated, additional walls cooperating with said walls to form an air passage completely encircling said space and having a hot air entrance, a hot air exit near the heater and a room air inlet further from the heater, a thermostat in said passage above the room air inlet, adjacent said heat insulating space and distant from the hot air outlet, and means governed by the thermostat for controlling the flow of combustion air to the heater from said room air inlet whereby when said means nearly shuts off air to the heater, a flow of cold air will be induced in said air passage from the room air inlet past the thermostat to the hot air outlet, thereby making the thermostat responsive

to room temperature almost exclusively when the heat requirements of the room are substantially met.

3. The device of claim 2 in which the air passage includes three parallel baffles between the thermostat and the space heater at least one of the walls being of a reflecting surface.

4. In a draft regulator for space heaters of the type burning solid fuel, a damper for controlling the admission of air to the stove, walls forming a vertical passageway conducting heated air from the stove upwardly, walls forming a second vertical passageway, a thermostat within said second passageway and operatively connected to the damper to increase or diminish the flow of air to the stove, a horizontal air passageway communicating with said two passageways, and means cooperating with the walls to form a ventilated air space between said vertical passageways and below said horizontal passageway located at substantially the elevation of the thermostat, said air space serving to cool the walls of the passageways to a temperature only slightly above that of the room.

5. In a regulator for a solid fuel burning heater, a damper for controlling the admission of main combustion air to the heater, a thermostat operating said damper, and a series of walls between the heater and the thermostat for shielding the thermostat from radiant heat from the heater, said walls providing a portion of the boundary of an air passageway, alternately directing room temperature air and heater warmed air to the thermostat as the damper is opened and closed, a plurality of said walls having heat reflecting surfaces facing in the direction of the heater.

6. The device of claim 5 in which at least one of said walls is a wall of a ventilated heat insulating space substantially at the level of the thermostat.

7. In a regulator for a heater, a metal framework, a thermostat adjustably carried by said framework, means controlled by the thermostat for regulating the heater, a casing surrounding the framework on three sides, and projections on said frame-work for holding the casing in spaced relation to the frame-work in order to provide an insulating air space between the casing and the frame-work, whereby to shield the thermostat from heat from said heater passing through the casing walls.

8. In a heat regulator for a room heating stove, a pair of vertical walls, a sloping wall joining said walls to form three sides of a heat insulating space of which the sloping wall is the bottom, a thermostat mounted adjacent one of said vertical walls, means controlled by said thermostat for regulating the stove, and means including said sloping wall for directing air heated by the stove downwardly past the thermostat and toward the vertical wall further from the thermostat, said heat insulating space being open to room temperature and located between the stove and the thermostat.

PERRY S. MARTIN.
